(57) **CLAIM**

The ornamental design for a decorative rocker switch, as shown and described.

DESCRIPTION

FIG. 1 is a perspective view of a decorative rocker switch having a window panel which is not centered on the center line of the rocker;

FIG. 2 is a top view of the decorative rocker switch of FIG. 1;

FIG. 3 is a bottom view of the decorative rocker switch of FIG. 1;

FIG. 4 is a side view of the decorative rocker switch of FIG. 1, the other side view being the same;

FIG. 5 is a top end view of the decorative rocker switch of FIG. 1, the bottom end view being the same; and,

FIG. 6 is a perspective view of the decorative rocker switch of FIG. 1 showing an intended environment in phantom.

The broken line showing of the environment is for illustrative purpose only and forms no part of the claimed design.

1 Claim, 2 Drawing Sheets
